(57) **CLAIM**

The ornamental design for a transparent card with a machine readable stripe, IC chip and ornamental rectangle, as shown.

DESCRIPTION

FIG. 1 is a perspective view of a transparent card with a machine readable stripe, integrated circuit (IC) chip and ornamental rectangle showing our new design;

FIG. 2 is a front view of the card of FIG. 1;

FIG. 3 is a rear view of the card of FIG. 1;

FIG. 4 is a right side elevational view thereof;

FIG. 5 is a left side elevational view thereof;

FIG. 6 is a front elevational view thereof; and,

FIG. 7 is a rear elevational view thereof.

The numerals and indicia depicted by means of broken lines in the drawing figures have been shown for illustrative purposes only and form no part of the claimed design.
